UNITED STATES PATENT OFFICE.

RUSSEL G. WOODWARD, OF WAUKEGAN, ILLINOIS, ASSIGNOR TO, UNION SPECIAL SEWING MACHINE CO., OF CHICAGO, ILLINOIS, A CORPORATION OF ILLINOIS.

SEWING-MACHINE.

No. 923,750.

Specification of Letters Patent

Patented June 1, 1909.

Application filed August 3, 1901. Serial No. 70,795.

To all whom it may concern:

Be it known that I, RUSSEL G. WOODWARD, a citizen of the United States, residing at Waukegan, in the county of Lake, State of Illinois, have invented certain new and useful Improvements in Sewing-Machines, of which the following is a description, reference being had to the accompanying drawing, and to the letters and figures of reference 10 marked thereon.

My invention relates to certain improvements in sewing machines of that type in which the threads are interlocked to form stitches above the fabric before the needle 15 enters the same, and while applicable to any machine of this class, is especially adapted for use in connection with a machine of the single interlock type, such as shown and described in an application for Letters Patent, 20 filed by me on the 8th day of April, 1901, Serial No. 54,897. In this type of machine, the needle reciprocates continuously in the same vertical plane, and an oscillating looper is employed to carry a separate thread 25 in front of, and very close to the needle, the descent of the latter causing the needle thread to bind over the looper thread and confine the same to the upper surface of the fabric.

It is found in practice, especially in machines making a very short stitch, that the looper must travel very close to the needle, as there is absolutely no friction to throw out a loop from the looper, and the needle must pass over the looper thread while the latter 35 is in a substantially straight line. The looper travels in a fixed circular path and in assembling the machine, is so adjusted as to travel as close as possible to the front of a needle. When so adjusted, and a small 40 sized needle of the ordinary type is employed, the machine works satisfactorily, and will seldom or never miss a stitch. When, however, a large sized needle is employed for a different class of work or to accommodate a larger thread, the point of the 45 needle is, owing to its greater diameter, removed to a considerable distance from the looper and the formation of a perfect stitch is rendered uncertain.

The objects of the present invention are: 50 first, to provide in connection with a moving looper, a needle of such construction as to positively insure the interlocking of the looper thread, and second, to maintain a uniform 55 form or substantially uniform distance be-

tween the needle point and looper, regardless of the size of needle employed, the machine being thus rendered capable of adjustment to work of varying character, without danger of missing stitches. To this end, I 60 employ a needle having its front side in a straight vertical line from shank to point, the rear side being curved or inclined toward the front to form a sharp point at the lower end, and such point being in a plane with the 65 front or straight side of the needle.

In the accompanying drawing:—Figure 1 is a perspective view of sufficient of the working parts of a sewing machine to illustrate the application of my invention; Figs. 2 is an elevation on an enlarged scale, of the front side of the needle; Fig. 3 is a sectional elevation of the same, on the line 3—3, Fig. 2; Figs. 4 and 5, are respectively a rear and a side elevation of the needle; and Fig. 6 is a sectional plan 75 view of the needle on an exaggerated scale.

Referring to the drawing, A represents the needle bar, B, the presser foot, S the work support, and M, a looper carrying shaft to which is secured a curved looper L arranged 80 to be moved in a curved path around the front of the needle and carry a thread x for engagement with the needle thread x'. At the rear of the needle bar is a hook c, which is employed to catch the loop of the needle 85 thread under the fabric, and draw it up to a point where it may be engaged by the looper L, forming an overedge stitch, the needle thread being interlocked by the looper thread above the fabric.

Each movement of the needle binds the looper thread to the fabric, and as the looper moves around in front of the needle, the thread is drawn somewhat taut, and, as there is no friction to throw out a loop, the 95 needle must work very close to the looper to engage the thread of the latter.

When the usual type of needle is used, the point being in the center of the stock, the point is necessarily removed from the looper 100 for a distance equal to half the diameter of the needle, plus the necessary space between the side of the needle and the looper. In a heavy needle, the distance between the point and looper is so great as to render uncertain 105 the formation of a perfect stitch, and I, therefore, propose to make the point to one side of the center of the stock, and so bring it nearer the looper.

The needle C has its front side c in a per- 110

fectly straight vertical line from point to stock, and its rear side is curved or inclined at the lower end, at c' , so that the point is formed in a plane with the straight front face, bringing it close to looper. In order to render a very close working possible, the face c is provided with a groove c^2 , from the eye c^3 , to the stock, the thread lying closely in the groove, and out of contact with the looper. The result of this construction is that the point of the needle will at all times enter between the looper and its thread and positively insure the interlocking of the threads.

15 Needles of small, or of large diameter may be employed, but in all cases, the flat side and point will be the same distance from the looper, and will not vary as would be the case with needles having their points in the center 20 of the stock.

Having thus described my invention, what

I claim as new, and desire to secure by Letters Patent, is:—

A sewing machine, including in combination a work support, a needle, complementary 25 stitch-forming mechanism including a thread carrying implement, adapted to carry its thread across the upper surface of the work support in position for the entrance of the needle into the loop of thread on said implement, said needle having its point located in a line with the face of the needle nearest the path of movement of the thread-carrying implement, whereby said needle point will with certainty pass between the said implement and the thread carried thereby.

In testimony whereof I affix my signature, in presence of two witnesses.

RUSSEL G. WOODWARD.
